(57) **CLAIM**

The ornamental design for a sensor mount for a self-driving car, as shown and described.

DESCRIPTION

FIG. 1 is a perspective view of the sensor mount for a self-driving car showing our new design.

FIG. 2 is a front view of the sensor mount for a self-driving car shown in FIG. 1.

FIG. 3 is a rear view of the sensor mount for a self-driving car shown in FIG. 1.

FIG. 4 is a left view of the sensor mount for a self-driving car shown in FIG. 1.

FIG. 5 is a right view of the sensor mount for a self-driving car shown in FIG. 1.

FIG. 6 is a top view of the sensor mount for a self-driving car shown in FIG. 1; and,

FIG. 7 is a bottom view of the sensor mount for a self-driving car shown in FIG. 1.
